UNITED STATES PATENT OFFICE

2,654,586

DIGGING MACHINE FOR MINING COAL

Charles Edward Berry, Fairmont, W. Va., assignor to Goodman Manufacturing Company, Chicago, Ill., a corporation of Illinois

Application February 4, 1950, Serial No. 142,489

8 Claims. (Cl. 262—19)

1

My invention relates to a digging head for machines, particularly adapted to the mining of coal and materials of similar nature, my particular object being the production of a machine that will conduce to safety, increase production of coal, and promote more economical mining.

Heretofore, it has been common practice in mining coal to first undercut the coal, then bore or drill holes to receive explosives, then shoot or blast to break the coal from the solid, and then load, either by hand or mechanical means, onto conveyors, cars or other suitable means of transportation.

The nature of these operations permits only one operation to be performed at one time, and requires the movement of men and machines into and out of the working place with each operation, thereby causing loss of productive time.

This practice requires numerous machines which are non-productive during considerable periods of time.

The use of explosives in the mine to break down the coal is known to have numerous disadvantages and hazards. The combination of cutting, drilling, shooting and loading produces finely divided dust particles which are hazardous to both life and property and objectionable to consumers of coal.

Heretofore, machines have been constructed to eliminate some of the objectionable features, but such machines all have numerous and known disadvantages. One of the most important of these is the finely divided dust particles, or fine slack, produced by machines using the cutting chain principle which, in effect, cuts or shears the coal from the solid, dragging and grinding the coal from the cut. Another disadvantage is the numerous moving parts, such as chains, links, pins, levers and wheels, which are subject to excessive wear. Some machines employ the wedge principle, others a shearing blade, and still others force bits or rods into the body of the coal to break it down. All these, and others, have one common disadvantage of requiring great quantities of power due to the fact that they work against the greatest strength of the coal, that is its shear and/or crushing resistance, and its great internal resistance due to internal compression of solid coal.

The structure of coal offers least resistance to impact force, as is readily demonstrated by dropping coal onto any solid surface.

Inspection of coal under a microscope shows that it contains minute cracks and crevices, and is composed of minute layers or laminations or

2

of granular particles. In its natural form when surrounded by other coal or covered with rock or overburden, these laminations and particles are bound together with considerable compression and offer great resistance to any penetration or disruption.

The exposed surface of coal, however, being relieved of such compression, immediately offers lower resistance. Such exposed surface has, in fact, a tendency to expand and crack along the lines of the minute cracks and laminations.

This effect penetrates for some depth into the coal, the depth varying with the structure of the particular coal being considered. In general, however, most coals are easily chipped or penetrated, with very slight force, to a depth of three-eighths of an inch upward to one and one-half inches. This fact is readily proven by means of a testing machine designed to remove chips or sections of coal by means of impact force. Tests prove that the amount of force required does not increase in proportion to the amount of coal or section removed but that, as the depth of section is increased, the force required, per unit of coal, increases rapidly. This effect of chipping the exposed surface of coal with small force is further demonstrated by a man using a common coal pick. With very slight effort, and in fact with the weight of the pick alone, by directing the pick downward and outward in a circular motion, a small section or chip or particle of coal will be removed. Tests with such an impact machine show that one-half cubic inch of coal is readily removed, from average coals, with a force of ten foot pounds.

These considerations lend themselves to a convenient and economical method of mining coal, and my invention proposes to take advantage of the weakness of coal to resist impact force and of the lower resistance of the exposed surface of coal by providing a digging head with rotating and vibrating bits which will, by impact force, remove or separate a small thin section of coal from its exposed surface, removing said coal in the form of small lumps or chips and removing said coal in a continuous manner. The method of doing this will be shown as the description proceeds.

An object of this invention is to produce a machine which will permit continuous mining and thereby eliminate non-productive time.

Another object is to produce a machine which will do the work previously performed by several machines.

Another object is to produce a machine which

will eliminate the use of explosives in the mine and thereby conduce safety.

Another object is to reduce the amount of fine coal, or dust, produced by prior mining methods.

Another object is to provide a machine which will mine a higher percentage of stoker, or peat-size coal, which is most suitable for stokers or mechanical burning equipment.

Still another object is to produce a machine which will mine coal in a reasonably uniform size most readily handled by conveying equipment.

Another object is to provide a machine which will produce coal of a reasonably uniform size so that a minimum amount of crushing or other preparation is subsequently necessary.

A further object is to provide a machine with a minimum number of working and wearing parts, of simple construction.

These and other objects will be apparent from the following description, and reference to the attached drawings, in which:

Figure 1 is a plan view showing my improved form of digging head applied to a mining machine, with the head in digging operation in a mine;

Figure 2 is an enlarged fragmentary detailed section of the front end of the mining machine shown in Figure 1, taken generally along the axis of rotation of the digging head;

Figure 3 is an enlarged detailed section taken on line 3—3 of Figure 2;

Figure 4 is a detailed section taken on line 4—4 of Figure 2, drawn to the same scale as Figure 3;

Figure 5 is a side view of the front end of the machine, drawn to a slightly larger scale than Figure 2, but showing the digging head and elevating frame therefor adjusted to a higher digging level;

Figure 6 is a fragmentary detailed section of the digging head and immediately associated drive and support means therefor, taken along the axis of rotation of said digging head and drawn to a larger scale than Figure 2;

Figure 7 is a detailed front view of the universally mounted support for the rear end of the digging head;

Figure 8 is a side view of the parts shown in Figure 7;

Figure 9 is a detailed face view of the universal joint for driving the outer hollow shaft of the digging head;

Figure 10 is a side view of the part shown in Figure 9;

Figure 11 is a detailed face view of the rubber insert ring forming part of the universal joint shown in Figures 9 and 10;

Figure 12 is a detailed section through the rotary digging head, taken on line 12—12 of Figure 6; and

Figure 13 is a diagrammatic view illustrating the principle of operation of the rotary digging head as it removes the coal from the working face.

Referring now to the embodiments of my invention, and first to details of construction of the digging head which forms the principal feature of my invention, 1 indicates a rotatable cylindrical shell to which are attached a plurality of digging bits 2, 2a projecting from the sides and closed front wall thereof. 3 is an off-center weight attached to a shaft 4. A tubular shaft 5 is attached to the inner end of shell 1 and to a flexible shaft coupling 6. Bearings 7 and 8 in the shell 1 and hollow shaft 5 support shaft 75

Shaft 4 is attached to flexible shaft coupling indicated generally at 9. It is apparent that rotation of this off-center weight 3 will create vibration, and that said vibration will be transmitted to the shell 1 and to the adjacent parts of the machine.

The tubular shaft 5 is supported at its rear end by the annular bearing 10, forming part of a universal joint type support indicated generally at 11, so that vibration set up in the shell 1 by the weight 3 will terminate at the common center line of the universal support 11 and flexible shaft couplings 6 and 9 and will not be transmitted to other bearings, gears, motors and their supporting structure, to be presently described in detail.

The guiding or controlling support for the digging head is provided by the bearing 12, in which shaft 5 turns. Arms 13 are pivotally connected radially about bearing 12 and the ends of the arms 13 are fitted into the ends of tubular arms 14 with a sliding fit. In the form herein, three tubular arms 14 are provided disposed in planes substantially at right angles to each other about shaft 5, with one arm above the bearing 12 and the two other arms at opposite sides thereof. Said arms are connected at their rear ends to frame members 30 and 31 forming part of an elevating frame or support indicated generally at 37, which will hereinafter be more fully described.

Springs 15 are provided to fit over each of the arms 13, one end of each such spring being seated against the end of arm 14 and the other end being seated against a nut 16 threaded on arm 13. It is evident from this construction that adjustment of the nut 16 will change the compression of spring 15 and thereby control or damper the vibration created by the off-center weight 3 with respect to the main supporting structure for the digging head.

In addition, a fourth arm 14a extends forwardly from an elevating frame 37, which will presently be described in detail. In the form shown, the arm 14a has a pair of upright springs 15a, 15a in supporting engagement beneath the bearing 12 to provide a floating support for the digging head. A thrust collar 12a is fixed as by welding on the shaft 5 in engagement with the front end of bearing 12.

The tubular shaft 5 is connected through a flexible coupling, indicated generally at 6, to a tubular shaft 17 rotatably mounted on the mobile base 37 and driven through power means thereon, as will presently be described.

Rotation of the tubular shaft 5 will furnish rotary motion to the shell frame 1 and bits 2, causing the bits 2 to rotate around the fixed axis A—A of Figure 6.

The shaft 4, on which the weight 3 is keyed, is connected through a flexible coupling, indicated generally at 9, to a driven shaft 18. As will be seen in Figures 6, 9, 10 and 11, the flexible coupling 6 is formed by tongues 5a and 17a forming parts, respectively, of collars 5b and 17b fixed to the abutting ends of the tubular shafts 5 and 17, and an intermediate rubber ring 6a having radially extending spokes 6b, 6b fitting between adjacent tongues 5a and 17a. The flexible coupling 9 consists of interfitting tongues 4a and 18a forming parts of collars 4b and 18c fixed to the abutting ends of shafts 4 and 18, and intermediate rubber ring 9a, similar to but smaller than ring 6a of coupling 6, interposed between adjacent tongues 4a and 18a of coupling 9.

5

Many conventional methods for movably supporting the rotary shell frame and for driving the shafts 17 and 18 may be provided. In the illustrative form of supporting and driving mechanism shown herein, a structure very similar to conventional supporting means for kerf-cutting machines is employed, including a base frame 35 having a turntable 36 mounted thereon and an elevating frame 37 vertically adjustable on the turntable, with the digging mechanism connected to, and projecting from, the front end of said elevating frame.

The base frame 35 may, as usual, be provided with a pair of endless tread supports 40, 40 along opposite sides thereof, driven from motors 41, 41 as usual, through suitable gearing, indicated generally at 42, at the rear end of said base frame.

The turntable 36 is pivoted about an annular upstanding bearing 45 disposed toward the front of the base frame. Power means for rotating the turntable may consist, as usual, of a motor 46, herein of the hydraulic type, connected by intermediate gearing, indicated generally at 47, to a spur gear 48 having teeth meshing with peripheral teeth surrounding the turntable.

The elevating mechanism for the elevating frame 37 consists of four upright hydraulic cylinders 50, 50 mounted on the upper face of the turntable at widely spaced points and projecting upwardly through apertures 49 in the elevating frame 37 (see Figure 3). Said hydraulic cylinders have pistons 51, 51 projecting through their upper ends and connected to L-shaped supporting brackets 52, 52 which depend along the sides of the cylinders and are connected to the bottom plate 37a of the elevating frame 37 adjacent the corners thereof.

The frame members 39, to which the laterally extending arms 14, 14 of the digging element are connected, is fixed to the front end of the bottom plate 37a of the elevating frame 37. The frame member 31, to which the upright arm 14 is connected, consists of a bracket fixed to the top of a cylindrical bearing member 55 in which hollow shaft 17 is journalled. The fourth arm 14a extends forwardly from the bottom plate 37a and is cut away at 56 to accommodate the lower part of universal joint 11 (see Figure 2).

The frame members 39 also support the universal joint member, indicated generally at 11, therebetween on horizontally extending trunnions 57, 57. Said universal joint member 11 includes an outer annular member 58 with a second circular member 59 connected thereto by upright trunnions 60, 60. The inner universal joint member has a plurality of forwardly projecting arms 61, 61 connected to the bearing 10, previously mentioned, in which the tubular shaft 5 of the digging arm is rotatably mounted. As will be seen from Figure 6, the universal joint 11, which supports the bearing 10, the universal joint 6 which connects the tubular shaft 5 with its drive shaft 17, and the coupling which connects the inner shaft 4 with its drive shaft 18, all are in mutual registering relation with each other longitudinally of the shafts named, so that the tubular shaft 5 and the inner drive shaft 4 are capable of limited universal tilting movement relative to the elevating frame 37, under control of the arms 14 and 14a and spring 15, 15a.

Independent drive means for the tubular shaft 5 and the inner drive shaft 4 consists of two electric motors 65 and 66 mounted on opposite sides of the elevating frame 37. The motor 65 for driv-

6

ing the inner shaft 4 has an armature pinion 67 at its rear end, connected through suitable gear reduction mechanism, indicated generally at 68, in gear housing 69 to a gear 18d fixed on the rear end of shaft 18 which is connected to the shaft 4 through the universal joint 9, as previously described.

The second motor 66 for driving the tubular shaft 5 has a motor pinion 70 at its rear end connected through suitable gear reduction mechanism, indicated generally at 71, to a gear 72 fixed on the rear end of the tubular shaft 17. Said tubular shaft 17 extends forwardly and is connected to the tubular shaft 5 through the universal joint 6, as previously described.

The motors 65 and 66 are provided with independent current supply and controllers of any conventional form (not shown), so that the two shafts 4 and 5 may be driven independently of each other at different speeds and in the same or reverse directions, as desired.

Any suitable means for removing and loading out the coal cut away from the coal seam by the rotary digging head may be provided. In the illustrative form of loading out apparatus shown herein, the front end of the base frame 35 is provided with a plurality of radial spokes 73 connected to a circular guide member 76, which is concentric with the turntable axis, and also extends beyond the front portions of the endless trades 40, 40. The turntable 36 has an arm 80 which extends forwardly beneath the arm 14a, with a depending portion 81 normally in bearing engagement with the outer face of the guide member 76. An arcuate scraper 82 is pivotally connected by an upright pivot pin 83 to a lateral extension 84 of depending portion 81. The scraper 82 has an arm 85 extending beyond its pivot pin and engaging the rear face of the lateral extension arm 84, to hold the scraper in proper angular position as the turntable is swung in a counter-clockwise direction, as seen in Figure 1, so that the scraper follows closely behind the rotary digging member and gathers the coal fragments which have been dislodged from the coal face and deposited on the mine floor.

When the turntable 36 is moving in a clockwise direction to return the cuttings head to a starting position to a subsequent pass of the rotary cutting head across the coal seam, the scraper arm may turn a limited amount about the pivot pin to assist in a relatively unimpeded return movement of the scraper to the starting position. As the digging proceeds toward the left-hand side of the room, the coal fragments gathered by the scraper will be moved toward the left side of the machine, in position to be loaded on the feeder head of a conventional shaker conveyor, indicated generally at 86. The details of construction of the shaker conveyor need not be further shown nor described, since it forms no part of the invention and other forms of loading devices may be used for removing the loose material from along the working face.

The use and operation of the digging head, as above described, is as follows:

Since the shell 1 of the digging head can be rotated by its drive motor 66 independently of, and at a different speed than, the weight 3 driven from the motor 65, any desired vibration force can be obtained by selecting a suitable weight 3, after including and considering the weight of the shell 1 and its associated parts, and selecting a suitable speed of rotation for weight 3. Further, by means of properly coordinating the speed of

rotation of the shell 1, with the vibration created by the weight 3, the bits 2 can be caused to vibrate a desired number of times per revolution of shell 1.

This combination of rotating and vibrating the bits 2 is the force utilized in the present invention, to secure digging or mining action. The action of the digging head is best illustrated diagrammatically in Figure 13, in which is shown by dotted line the outer circumference of shell 1 and a single bit 2. The center of rotation of shell 1, or axis A—A of Figure 6, is represented by the intersection of the vertical and horizontal center lines of Figure 13. For further illustration, a section of solid coal 21 is shown. With a given mass of the shell 1 and its associated parts, a given mass and relative speed of rotation of the weight 3, and a given tension on the springs 15, the center of rotation of the shell 1 will oscillate about an approximate path, indicated at 20, within fixed limits and with controlled force. Also, the bit 2, or more exactly the point of bit 2, will oscillate on the dotted line 22.

Then, if the oscillation path of the bit 2 partly intersects the body of the coal, as further shown by the dotted line 22, the impact force of the entire digging head will be delivered to the coal. If this force be greater than the resistance of the coal, a section of coal, as indicated within the dotted line 22, will be removed.

If no other movement were now applied to the bit 2, it would merely continue to oscillate on the dotted line 22. I, therefore, provide for the rotation of the bit 2 around its axis A—A, as previously shown. This rotation will bring the point of bit 2 successively into new positions and cause it to come in contact with new sections of coal. As long as rotation and vibration continue, the bit will approximately follow the path of dotted line 23, thereby digging or mining additional coal at each vibration.

By means of properly coordinating the rotation of the bits with the vibration of the bits, coal can be dug or mined approximately along the line 24, although it is not intended to infer that coal will be removed in regular and uniform sections as shown, for the coal will usually break out in highly irregular sections along the lines of lamination and fracture.

For illustrative purposes, only one bit has been considered in connection with the diagram in Figure 13. The same digging effect is attained in practice, providing the shell 1 has a plurality of digging bits 2, as shown in Figures 1, 5 and 6.

While it is evident that the digging head may be employed as a drilling or boring tool by feeding it forwardly in the direction of its axis A—A, it will be understood that it operates most effectively by swinging it in planes transverse to its axis A—A thereto, or in any angle thereto, as indicated by the arrows 25 in Figure 13.

Referring now more generally to the use and operation of the digging head in conjunction with the form of supporting base 32 shown in the drawings, said base is capable of introducing or summing the digging head and its associated parts into the coal face in several different ways and at varying angles to the coal by manoeuvering the base on its endless treads 40 with the turntable 36 disposed at varying angles with respect to the coal face.

In the illustrative method shown in Figure 1, the machine is employed for advancing a room or entry along a generally straight room or en-

try with parallel side walls 90, 90, which is formed by swinging the digging head and its supporting members through an arc of 180 degrees from one side of the machine to the other, to form an arcuate working face 91 at the advancing end of the room or entry. It will be understood that this mining operation is carried out by summing the digging shell 1 when it is disposed at a right angle to the longitudinal axis of the machine as the latter is positioned in the center of the room. In Figure 1, the initial summing position of the digging head is shown in dotted lines. By swinging the digging head under power in an arcuate path about the front end of the machine with the entire machine moved forwardly on its endless treads 46 through a distance equal to that which the working face is to displace during one arcuate sweep, said digging head will remove the portion of the working face 91 to form a new arcuate working face, indicated at 92, for the full width of the room.

If the height of the coal seam to be mined is, as may often be the case, greater than the diameter of the digging shell 1 with its bits 2, the arcuate swinging movement of the shell 1 may be repeated with the elevating frame 31 raised to a higher position, as indicated in Figure 5.

It will be understood that the initial summing operation may also be carried out with the digging head disposed at less than a right angle to the line of advance of the machine as a whole, when a narrower room or entry is desired. In general, however, it will be borne in mind, as previously stated, that the digging effect of the shell 1 is most effective when the latter is advanced toward the coal in a general direction transverse to its normal axis of rotation. For this reason, it is obvious that best results will be attained by summing the digging head in a working face when it is at an appreciable angle to the direction in which the working face is being advanced, and thereafter swinging the digging head laterally across the working face.

This application is a continuation in part of my pending application Serial Number 39,905, filed July 21, 1948, now abandoned.

Although I have shown and described certain embodiments for the purpose described, it will be understood that I do not wish to be limited to the exact construction shown and described but that various changes and modifications may be made without departing from the spirit and scope of the invention as defined in the appended claims.

I claim:

1. In a digging machine, a base, a rotary digging head including an annular member having a plurality of peripherally mounted, radially extending digging members thereon for engagement with a working face, means yieldably supporting said annular member on said base, power means on said base operatively connected through said yieldable supporting means for rotating said annular member, an off-center weight mounted on and coaxial with said annular member for rotation independently thereof, and power means for driving said off-center weight at a speed different from said annular member to impart vibratory motion to the latter.
2. The structure in accordance with claim 1, wherein the means for driving the off-center weight is also mounted on the base and is op-

eratively connected to said weight through the yieldable supporting means.

3. The structure in accordance with claim 1, wherein the yieldable supporting means for the rotary digging head and off-center weight includes a pivotal supporting structure permitting universal axial tilting movement of said digging head and weight relative to said base.

4. The structure in accordance with claim 3, wherein the yieldable supporting means includes a plurality of springs supported on said base and yieldably supporting said rotary digging head and weight beyond said pivotal connection in a plurality of angular directions relative to their normal axis of rotation.

5. The structure in accordance with claim 4, wherein the tension on said springs is adjustable to control the vibratory action of said rotary head.

6. A device of the class described comprising an outer shell having peripherally projecting digging bits, a tubular shaft for rotating said shell, an off-center weight rotatable within the outer shell to create vibration of the latter, a shaft within said tubular shaft to rotate said weight, a frame having supporting arms with adjustable compression means surrounding the outer tubular shaft intermediate its ends for controlling the vibration of said shell and tubular shaft, means on said frame for supporting the adjacent inner ends of said shafts including flexible shaft couplings coincident with said last-

5

named supporting means, and power-driving means on said frame for driving said shafts independently of each other through their respective flexible shaft couplings.

7. A coal digging machine in accordance with claim 1, wherein power means is provided for feeding said annular member radially of its general axis of rotation.

8. A digging machine in accordance with claim 1, wherein the base is mounted on a movable frame for feeding movement in a direction transverse to the general axis of rotation of the rotary digging head, and power means is provided for moving said digging head relative to said frame for engaging the digging members on said head against a working face.

CHARLES EDWARD BERRY.
